DESIGN FOR A FOOD MIXER

Edward Richard Hacmac, Hollywood, Calif., assignor to Na-Mac Products Company, a corporation of California

Application October 28, 1938, Serial No. 80,733

Term of patent 14 years

To all whom it may concern:

Be it known that I, Edward Richard Hacmac, a citizen of the United States, residing at Hollywood, in the county of Los Angeles and State of California, have invented a new, original, and ornamental Design for a Food Mixer, of which the following is a specification, reference being had to the accompanying drawing, forming a part thereof.

In the drawing:

Fig. 1 is a front view of a food mixer embodying my novel design.

Fig. 2 is a side view thereof.

Fig. 3 is a top view.

I claim:

The ornamental design for a food mixer, substantially as shown.

EDWARD RICHARD HACMAC.
